UNITED STATES PATENT OFFICE.

MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

COMPENSATING AIR COMPRESSOR.

Application filed March 16, 1927. Serial No. 175,710.

This invention relates to air compressors and the primary object of the invention is to provide a balancing arrangement which will compensate for unbalance of load of a compressor and give equal loading on both forward and return strokes, thereby reducing peak loads, uneven torque effort, and which, due to the relief of frame loads will allow the use of a relatively small frame.

10 The present invention comprises a compensating air compressor or balancing cylinder and piston arrangement in which the balancing cylinder is fitted with a suction valve which allows the cylinder to fill with air or gas under a relatively low pressure and the clearance space within the cylinder is proportioned so that the maximum pressure may be controlled by clearance to give the necessary balance between the forward and return strokes of the balancing non-compressing piston.

15 With these objects in view, the invention consists in various features of construction and combination of parts, which will be first described in connection with the accompanying drawings, showing a compensating air compressor of the preferred form embodying the invention, and the features forming the invention will be specifically 20 pointed out in the claims.

25 In the drawings—

Figure 1 is a longitudinal section through an air compressor showing the improved compensating or balancing piston and cylinder arrangement.

30 Figure 2 is an enlarged fragmentary view of a part of the compressor.

Figure 3 is a longitudinal section through an air compressor of the double acting type showing the improved compensating or balancing structure associated therewith.

35 In Figure 1 of the drawings, the improved compensating structure or balancing cylinder and piston are shown as associated with a booster compressor, or the last stage 40 of a multi-stage compressor for handling air or gas at relatively high pressures. In such constructions the small diameter of the piston necessitates a compressor of the plunger type, and due to nature of design, it must necessarily be single acting. In the present practice of constructing such machines very large frame bearing, crank and connecting rods are required, due to the extremely high peak loads and it also results

in uneven torque effort. When associated with this type of machine the improved balancing cylinder and piston structure will materially decrease the frame loads, thus allowing the use of a small frame and will 45 convert the characteristics from that of a single acting compressor to that of a two-stage compressor with the resulting advantages.

50 The high stage of booster compressor A of approved construction has associated therewith the balancing arrangement B and the operating mechanism C, which operating mechanism may be of any approved type, and while a particular construction of 55 booster or high stage compressor is illustrated, it is to be understood that the invention is applicable to such compressors irrespective of their particular details of construction.

55 The booster or high stage compressor A comprises the cylinder 1 which has the usual suction or inlet valve structures 2 and the outlet or discharge valve structures 3 and in operation, the air, gas or other fluid under 60 pressure is drawn into the cylinder 1 where it is compressed to a higher state of compression by action of the plunger piston 4 after which it is discharged through the discharge valve 3. In high pressure compressors where very high pressures are desired 65 the piston, because of its small diameter, must be of the plunger type and is necessarily single acting because of the nature of the design of such final stage compressors. 70 A single acting compressor requires very 75 large frame bearing, crank and connecting rods because of the extremely high peak loads and also results in uneven torque efforts. To balance the operation of the high 80 pressure compressor structure and change its 85 characteristics from that of a single acting to that of a two-stage compressor, a compensating or balancing non-working cylinder 5 is provided in which the balancing piston 6 90 reciprocates. The piston 6 is connected, 95 preferably by a flexible connection as indicated at 7 to the piston 4 of the high pressure compressor A and in the form illustrated in the drawings the piston 6 is connected 100 by a connecting rod 8 through the cross head structure 9 with the operating shaft 10 of the operating mechanism C so that the compensating or balancing cylinder 105 and piston structure is interposed between 110

the high pressure compressing piston 4 and its operating mechanism. This construction is a matter of relation of the parts and it is to be understood that the balancing cylinder 5 and non-working balancing piston 6 may be positioned at any desired or convenient place relative to the high pressure compressing piston 4 so long as they will properly balance the action of the compressor A and 10 perform their functions. The balancing cylinder 5 has a valve structure 11 of any approved type at its suction or inlet. In the drawings, the valve 11 is shown as of the well known type of the Meyer patents Re-issue #13,991 and #1,341,145 but it is to be understood that any suitable valve may be provided. The valve 11 establishes communication between the inlet space or chamber 12 and the cylinder 5. The chamber 12 has an inlet opening 13 therein which may be opened to the atmosphere or if it is so desired may be connected to an inter-cooler of 20 a multi-stage compressing installation so as to receive air or gas into the chamber under 25 a relatively low pressure.

The suction valve 11 will admit air or gas into the cylinder 5 behind the piston 6 only in sufficient quantity to fill the clearance space 14 in the cylinder 5 and this clearance space 14 is proportioned to provide the proper pre-determined maximum pressure in the cylinder to properly compensate or balance the action of the high pressure compressing piston 4.

35 In operation, upon the suction stroke of the piston 4 the balancing piston 6 will compress the air or gas in the clearance space 14 of the cylinder 5 and upon the compressing stroke of the piston 4 the air or gas which has been compressed in the clearance space 14 will exert its expanding energy against the piston 6 and, consequently, against the high pressure compressing piston 4 and by proportioning of the size of 40 the clearance space 14 the proper pressure may be provided against the piston 6 on both its forward and return strokes to properly 45 compensate the action of the piston 4 depending upon the work performed and effort 50 required by the piston 4.

In case of leakage of any of the air or gas from the clearance space 14 past the balancing piston 6 the said air or gas will pass through the opening 17 into the chamber 12 and be returned to the cylinder 5 through the suction valve 11.

55 In Figure 3 of the drawings the improved compensating or balancing structure is shown associated with an air or gas compressor of double acting construction. In double acting compressors the diameter of the piston rod deducts from the compressing area of the piston on the crank end of the cylinder and causes the machine to be unbalanced to such an extent that the load on

the crank end will always be negative, giving the same loading effect as the single acting construction above described. The compensating or balancing structure will compensate for such unbalance and give 70 equal loading on both forward and return strokes of the compressing piston.

The double acting air compressor includes the compressing cylinder 20 in which the compressing piston 21 reciprocates and as 75 this type of compressor is double acting the piston 21 compresses air or gas upon both its forward and return stroke and while the area of the cylinder is the same on both sides of the piston 21 the active or compressing area of the piston 21 on the crank end of the cylinder is reduced by the diameter of the connecting rod 22 which results in unbalancing the action of the machine as above referred to. To compensate for 80 this unbalancing a balancing or compensating cylinder 24, which is non-working is provided in which the non-working balancing piston 25 reciprocates. The non-working balancing piston 25 is connected to the 85 connecting rod 22 by any suitable type of coupling as shown at 26 and it is also connected through the medium of the connecting rod 27 and crosshead 28 with the operating shaft 29. The cylinder 24 has a valve 90 structure 30 of any approved type at its suction or inlet and in fact the balancing or compensating structure associated with the double acting compressor is similar in construction to the balancing cylinder 5, 100 piston 6 and their companion parts as shown in Figure 1 and described in connection with said figure. The inlet space or chamber 31 is also provided which is open either to the atmosphere or may be connected to an inter-cooler of a multi-stage compressing installation and receives air or gas in the chamber under a relatively low pressure which air or gas is drawn into the clearance space 32 in the cylinder 24 as needed. The clearance space 32 is proportioned to provide the proper pre-determined maximum pressure in the cylinder 24 to properly compensate or balance the action of the compressing piston 21 and give equal loading on both forward 105 and return strokes of the piston 21. A suitable opening 33 is provided to permit return to the chamber 31 of air or gas which escapes past the piston 25 in its operation.

110 In the foregoing specification and drawings the improved compensating or balancing cylinder and piston arrangement has been described and shown as applied to a high pressure air or gas compressor but it is to be understood that the invention is not 115 to be limited to such particular application but may be used in connection with single acting high pressure pumps or analogous mechanism, without departing from the spirit of this invention.

It will be understood that the invention is not to be limited to the specific construction or arrangement of parts shown but that these may be modified widely within the invention defined by the claims.

What is claimed is:

1. In an air or gas compressor, the combination with a compressing piston, of a balancing cylinder provided with a valved inlet and not having a discharge, and a balancing piston in said cylinder whereby air or gas in the cylinder will be compressed upon one stroke of the balancing piston and will exert its expanding force against the piston upon the other stroke.

2. In an air or gas compressor, the combination with a compressing piston, of a balancing cylinder closed from discharge, and a balancing piston in said cylinder whereby air or gas in the cylinder will be compressed upon one stroke of the balancing piston and will exert its expanding force against the piston upon the other stroke.

3. In an air or gas compressor, the combination with a compressing piston, of a balancing cylinder closed from discharge, a balancing piston in said cylinder whereby air or gas in the cylinder will be compressed upon one stroke of the balancing piston and will exert its expanding force against the piston upon the other stroke, and a passageway for directing air or gas leaking past said balancing piston to the inlet of the balancing cylinder.

35 4. In an air or gas compressor, the combination with a compressing piston, of a balancing cylinder closed from discharge, and a balancing piston in said cylinder whereby air or gas in the cylinder will be compressed upon one stroke of the balancing piston and will exert its expanding force against the piston upon the other stroke, said balancing cylinder proportioned to provide a pre-determined maximum pressure in the cylinder.

5. In an air or gas compressor, the combination with a compressing piston, of a balancing cylinder provided with a valved inlet and not having a discharge, a balancing piston in said cylinder whereby air or gas in the cylinder will be compressed upon one stroke of the balancing piston and will exert its expanding force against the piston upon the other stroke, said balancing cylinder clearance proportioned to provide a pre-determined maximum pressure in the cylinder.

6. In an air or gas compressor, the combination with a compressing piston, of a balancing cylinder closed from discharge, a balancing piston in said cylinder whereby air or gas in the cylinder will be compressed upon one stroke of the balancing piston and will exert its expanding force against the piston upon the other stroke, said balancing cylinder clearance proportioned to provide a

pre-determined maximum pressure in the cylinder, and a passageway for directing air or gas leaking past said balancing piston to the inlet of the balancing cylinder.

7. In an air or gas compressor, the combination with a compressing piston, of a balancing cylinder closed from discharge, a balancing piston in said cylinder and connected to said compressing piston, said balancing piston arranged whereby the air or gas in the balancing cylinder will be compressed upon the suction stroke of the compressing piston and will expand upon the compressing stroke of the compressing piston, whereby the compression and expansion of the fluid in the balancing cylinder acting upon the balancing piston will balance the action of the compressing piston.

8. In an air or gas compressor, the combination with a compressing piston, of a balancing cylinder provided with a valved inlet and closed from discharge, and a balancing piston in said cylinder and arranged whereby the air or gas in the balancing cylinder will be compressed upon suction stroke of the compressing piston and will expand upon compressing stroke of the compressing piston, whereby the compression and expansion of the air or gas in the balancing cylinder acting upon the balancing piston will balance the action of the compressing piston.

9. In an air or gas compressor, the combination with a compressing piston, of a balancing cylinder provided with a valved inlet and closed from discharge, and a balancing piston in said cylinder and arranged whereby the air or gas in the balancing cylinder will be compressed upon suction stroke of the compressing piston and will expand upon compressing stroke of the compressing piston, whereby the compression and expansion of the air or gas in the balancing cylinder acting upon the balancing piston will balance the action of the compressing piston, the clearance of said balancing cylinder proportioned to provide a predetermined maximum pressure in the cylinder.

10. In an air or gas compressor, the combination with a compressing piston, of a balancing cylinder provided with a valved inlet and closed from discharge, a balancing piston in said cylinder and arranged whereby the air or gas in the balancing cylinder will be compressed upon suction stroke of the compressing piston and will expand upon compressing stroke of the compressing piston, whereby the compression and expansion of the air or gas in the balancing cylinder acting upon the balancing piston will balance the action of the compressing piston, and a passage communicating with the cylinder and its inlet whereby any leakage of air or gas past the balancing piston will be returned to the balancing cylinder through its inlet.

11. In an air or gas compressor, the combination with a compressing piston, of a balancing cylinder closed from discharge, an inlet chamber for said balancing cylinder, a suction valve between said chamber and cylinder, a balancing piston in said cylinder, whereby air or gas in the cylinder will be compressed upon one stroke of the balancing piston and will exert its expanding force against the piston upon the other stroke.

12. In an air or gas compressor, the combination with a compressing piston, of a balancing cylinder closed from discharge, an inlet chamber for said balancing cylinder, a

suction valve between said chamber and cylinder, a balancing piston in said cylinder, whereby air or gas in the cylinder will be compressed upon one stroke of the balancing piston and will exert its expanding force against the piston upon the other stroke, said inlet chamber having communication with one end of the cylinder remote from the cylinder inlet whereby any leakage of air or gas past the balancing piston will be returned to the cylinder inlet through said chamber.

In testimony whereof I affix my signature.

MICHAEL RIESNER.
